Frank Danielson
Fabel & Mueller Atlys.

UNITED STATES PATENT OFFICE.

FRANK DANIELSON, OF CHICAGO, ILLINOIS.

WRENCH.

1,394,539.

Specification of Letters Patent.

Patented Oct. 25, 1921.

Application filed June 1, 1920. Serial No. 385,556.

To all whom it may concern:

Be it known that I, FRANK DANIELSON, a citizen of the United States, residing at Chicago, in the county of Cook and State of Illinois, have invented a certain new and useful Improvement in Wrenches, of which the following is a full, clear, concise, and exact description, reference being had to the accompanying drawings, forming a part of this specification.

This invention relates to wrenches and has for its object to provide a wrench with means whereby it can be readily determined when the transverse cotter pin opening in a bolt and the slots or openings in a castellated nut are in alinement.

Prior to this invention, it was necessary, in order to determine whether the cotter pin used for locking the nut on the bolt could be inserted, to remove the wrench and probe with the cotter pin to determine whether the openings receiving the same were in alinement. This usually had to be repeated many times thus necessitating the removal and replacement of the wrench numerous times. The present invention avoids entirely the necessity of removing the wrench to determine whether the said openings are properly alined. This is avoided by providing a transverse opening in the socket portion of the wrench through which a pin can be inserted to determine whether the openings are properly alined.

Referring to the drawings:

Figure 1 is an elevational view of wrench constructed in accordance with my invention showing the same engaging a nut on a bolt; Fig. 2 is a view partly in section on line 2-2 of Fig. 1 of the same showing a portion of the handle broken away; and

Fig. 3 is a section on the line 3-3 of Fig. 2.

The wrench shown in the drawings comprises a handle 4 and a jaw 5 secured thereto in any suitable manner as by a pin 6. The jaw 5 is in the form of a socket 7 corresponding to the outer surface of the nut 8. In the present case the same is shown as being hexagonal. This wrench is particularly adapted for use in applying a nut to a bolt that is locked thereto by a cotter pin (not shown) and for this purpose the bolt 9 is provided with a transverse opening 10 adapted to receive the cotter pin. The nut 8 is provided with a plurality of pairs of slots 11 extending inwardly from one of the ends

thereof and is what is commonly known as a castellated nut.

In tightening such a nut on a bolt provided with a transverse opening such as described it requires considerable manipulation with the ordinary form of socket wrench to get a pair of slots 11 and the opening 10 alined so as to readily insert the cotter pin therethrough. It is necessary with the ordinary form of wrench to remove the same in order to try to insert the cotter pin to see if the openings are properly alined, then if they are not properly alined it is necessary to again apply the wrench to give the nut a slight movement in attempting to aline the openings. This makes it necessary to frequently remove and replace the wrench on the nut before the nut is in its final position where the cotter pin can be inserted to lock the same.

In the present device the jaw 5 is provided with a transverse opening 13 slightly larger than opening 10 extending entirely therethrough diametrically thereof at the hexagonal portion 7 so located that the same would be substantially in line with the slots 11. In using this wrench when the nut is sufficiently tightened the cotter pin is inserted into the opening 13 to determine whether the slots 11 and transverse opening 10 are in alinement. If this is not the case the nut can be turned slowly so as to bring the slots 11 and opening 10 in alinement and at the same time the cotter pin can be used to probe for the slots and opening through the opening 13 to determine whether the same are in alinement, and as soon as it is possible to push the cotter pin entirely through from one end of the opening 13 to the other thereof the nut will be in its final position. This makes it possible to turn the nut on the bolt to its final position without removing the wrench to determine whether the cotter pin can be inserted and removes the objection to the old type of wrench which had to be frequently removed and replaced in order to properly aline the slots 11 and opening 10.

Having thus described the preferred form of my invention I desire to have it understood that I do not intend to limit myself to the exact details shown and described except as defined in the following claims:

1. The combination with a bolt provided with a transverse opening and a nut provided with paired openings adapted to be alined therewith, of a socket wrench pro-

- vided with means to indicate when one of said pairs of openings is alined with the opening in said bolt.
2. The combination with a blot provided with a transverse opening and a nut provided with paired openings adapted to be alined therewith, of a socket wrench provided with an opening to indicate when one of said pairs of openings is alined with the opening in said bolt by the insertion of a pin therein.

3. A socket wrench comprising a handle and a jaw portion provided with a socket adapted to receive a nut therein, and having a transverse opening through the socket portion of said jaw adapted to aline itself with a transverse opening in a bolt and with paired transverse openings in the nut for the purpose set forth. 15

In witness whereof, I hereunto subscribe 20 my name this 4th day of May, A. D. 1920.

FRANK DANIELSON.
